DESIGN FOR EMBROIDERED NEEDLEWORK FABRIC OR SIMILAR ARTICLE

Maurice Fixler, Chicago, Ill., assignor to Fixler
Bros., Chicago, Ill., a copartnership

Application August 26, 1948, Serial No. 148,302

Term of patent 3½ years

(Cl. D92—1)

To all whom it may concern:

Be it known that I, Maurice Fixler, a citizen of the United States, and a resident of the city of Chicago, in the county of Cook and State of Illinois, have invented a new, original, and ornamental Design for Embroidered Needlework Fabric or Similar Article, of which the following is a specification, reference being had to the accompanying drawing, forming a part thereof.

On the drawing the figure is a plan view of the embroidered needlework fabric or similar article, showing my new design.

I claim:

The ornamental design for embroidered needlework fabric or similar article, as shown.

MAURICE FIXLER.
